UNITED STATES PATENT OFFICE.

HARRY S. VROOMAN, OF CHICAGO, ILLINOIS.

DESIGN FOR FIRE-BRICK.

SPECIFICATION forming part of Design No. 30,288, dated February 28, 1899.

Application filed February 3, 1899. Serial No. 704,428. Term of patent 14 years.

To all whom it may concern:

Be it known that I, HARRY S. VROOMAN, a citizen of the United States, residing at Chicago, Cook county, Illinois, have invented and produced a new and original Design for Fire-Brick, of which the following is a specification, reference being had to the accompanying drawings, forming a part thereof.

Figure 1 is a perspective view of a fire-brick, showing my new design. Fig. 2 is an end view of the same.

As shown in the drawings, my design for fire-brick is rhomboidal in its general contour. It is formed with the upper edge *a* and the lower edge *a'* parallel, but with the cross-diameter of the former slightly greater than the corresponding diameter of the latter. The side faces *b* *b'* of the brick taper throughout their vertical diameters from the upper edge *a* inwardly to the lower edge *a'*. The side face *b* is broken at a point above the center of its vertical diameter by a groove *c*, which extends throughout the length of the brick

and is hemispherical in cross-section. The side face *b'* is broken by a shoulder *c'*, which is hemispherical in cross-section and extends throughout the length of the brick. The dimensions of the shoulder correspond exactly with the dimensions of the groove *c*, and said shoulder and groove are positioned exactly opposite each other in the respective sides of the brick. The ends *d*, only one of which is shown, are plane and parallel and are exact counterparts of each other.

Having thus described my invention, what I claim as new, and desire to secure by Letters Patent, is—

The design for fire-brick, substantially as herein shown and described.

I testify whereof I affix my signature in presence of two witnesses.

HARRY S. VROOMAN.
